UNITED STATES PATENT OFFICE.

EDWARD L. DEWEY, OF WHITING, INDIANA.

AUTOMOBILE-MUFFLER.

1,077,905.

Specification of Letters Patent.

Patented Nov. 4, 1913.

Application filed March 10, 1913. Serial No. 753,326.

To all whom it may concern:

Be it known that I, EDWARD L. DEWEY, citizen of the United States, residing at Whiting, in the county of Lake and State 5 of Indiana, have invented certain new and useful Improvements in Automobile-Mufflers; and I do hereby declare the following to be a full, clear, and exact description of the invention, such as will enable others 10 skilled in the art to which it appertains to make and use the same.

My invention relates to mufflers or silencers for the exhaust pipes of internal combustion engines, being particularly 15 adapted for use in connection with gasoline engines as used on automobiles.

The prime object of my invention is to provide a silencer adapted to be inserted in the exhaust pipe of the engine, which silencer 20 will simultaneously provide for the sound-muffling expansion of the exhaust gases and for utilizing the heat of the exhaust gases for warming the air-supply of the engine.

Another object is to provide a silencer of 25 simple construction and one which may easily be detached for cleaning the flues thereof.

Still another object is to provide means for causing the air drawn into the engine 30 to impinge upon a large surface of passages heated by the exhaust of the engine.

Other objects will appear from the accompanying drawings, in which—

Figure 1— is a view of a silencer and 35 air-heater embodying my invention. Fig. 2— is a longitudinal section of the same. Figs. 3— and 4— are transverse sections through Fig. 2— along the lines 3—3 and 4—4 respectively. Figs. 5— and 6— 40 are elevations of two of the air-deflecting partitions used in the embodiments of Figs. 1— and 2—. Fig. 7— is an alternative embodiment of my invention.

In the embodiment shown in Figs. 1—45 to 6— inclusive, the appliance of my invention consists of a flange 1 screwed to the exhaust passage 2 of the engine. Fastened to this flange are the smaller ends of a pair of concentric funnels 3— and 4—, the 50 larger ends of which funnels are secured by bolts 5— to the enlarged head 6 of a cylindrical casing 7. The other end of the casing 7 likewise has a head 8, the rim portion of which is connected by a tapering or 55 funnel-shaped shell 9 to the exhaust pipe 10. Within the casing 7 and mounted in

corresponding perforations in the heads 6— and 8—, are tubes 11 and 12—, through which the exhaust gases may pass from the interior 13— of the inner funnel 60 3—, to the tapering chamber 14 at the other end of the cylindrical casing and thence to the exhaust pipe 10—.

Connecting the radially projecting portion 15 of the head 6— with the adjacent end of the casing 7 is an annular flange 16—, which coacts with the head portion 15 and the adjoining end portion of the casing 7 to form an annular chamber 17—. Openings 18— in the casing and perforations 19— in the rim 15— of the head connect the chamber 17— with the interior of the casing and the space 20 between the two funnels 3— and 4— respectively. Near the other end of the casing 7—, the 70 latter has a number of openings 21— for admitting air from outside the casing to the interior of the same, while a pipe 22— screwed to the outer funnel 4— connects the chamber 20— with the air-intake passage of the engine. 80

When the engine in connection with which the muffler of my invention is used is in operation, the exhaust gases from the engine will pass from the pipe 2— into the chamber 13, in which these gases may expand rapidly and from which they may pass through the tubes 11— and 12— to the outward chamber 14— and thence through the pipe 10— to the outer air. 90

By making the total cross-sectional area of the tubes 11— and 12— considerably larger than that of the exhaust pipe 2— of the engine, the exhaust gases will be permitted to expand rapidly to many times their former volume while passing through the chamber 13— and the tubes 11— and 12—. Consequently, the usual noise of the exhaust will be effectively muffled. At the same time, the heat of the exhaust 100 gases will warm the tubes 11— and 12— and the air surrounding the latter within the casing. Hence the air for the operation of the engine will be warmed while being drawn through the openings 21— into the 105 casing, and through the chambers 17— and 20— to the intake pipe 22— of the engine. To prevent the air from passing from the inlet openings 21— to the outlet 110 openings 18— of the casing without contacting with a large portion of the outer surface of the pipes 11— and 12—, I

preferably provide transverse partitions —23— and —24— within the casing —7—, which partitions leave annular openings alternately close to the central pipe —11— and the casing —7—. When the casing of my muffler is thus equipped with transverse air-directing partitions, the intake air for the engine will be obliged to follow a sinuous path within the casing, somewhat as shown by the arrows in Fig. —2—. Consequently, the air will contact with practically the entire outer surface of the muffler pipes while passing through the casing and will be effectively heated by the exhaust gases passing through the said pipes. Likewise, the air while passing through the chamber —20— will be additionally warmed by the heat of the gases within the expansion chamber —13—.

While I preferably provide a series of transverse partitions for redirecting the air-currents within the casing and causing them to impinge repeatedly on the tubes within the casing, I do not wish to be limited to this construction, nor to other modifications which might be made in my device without departing from the spirit of my invention. For example, both the transverse air-deflecting partitions and the projecting rims of the heads of the muffler casing might be omitted, as in Fig. —7—, while still providing an effective noise-muffling expansion chamber and likewise providing for the warming of the intake air while passing through the casing. In either case, by removing the bolts —5— or —25—, the tapering ends of the muffler may readily be detached from the cylindrical portion thereof, thereby affording access to the interior of the tubes —11— and —12— for removing soot or other deposit. The inlet openings —21— of the casing are preferably placed radially out of line with the outer tubes —12— and preferably elongated longitudinally of the casing, but their shape, location and number may be varied as desired.

By providing an expansion chamber in which the exhaust gases may rapidly expand and by passing the air-supply for the carbureter of the engine through a chamber housing the said expansion chamber (whereby the exhaust gases may impart a portion of their heat to the intake air for the engine), and by likewise providing a large flue surface exposed on its opposite sides to the exhaust gases and the intake air respectively, I am able to effect a rapid expanding and cooling of the exhaust gases. Consequently, the muffler of my invention will effectively reduce the back pressure to an extent which has not been possible with the mufflers heretofore in use.

I claim as my invention:

1. A muffler for internal combustion engines, comprising a plurality of substan-

tially parallel tubes through which the exhaust of the engine is adapted to pass, the total cross-sectional area of the said tubes greater than the area of the exhaust pipe of the engine, and a casing housing the said plurality of tubes, there being openings leading from the interior of said casing to the outer air and to the air intake passage of the engine respectively. 70

2. A muffler for internal combustion engines, comprising a plurality of tubes through which the exhaust of the engine is adapted to pass, the total cross-sectional area of the said tubes greater than the area of the exhaust pipe of the engine, and a casing housing the said tubes, there being openings leading from the interior of said casing to the outer air and to the air intake passage of the engine respectively; and an air-deflecting partition within said casing 80 transverse to said tubes. 85

3. A muffler for internal combustion engines, comprising a plurality of tubes through which the exhaust of the engine is adapted to pass, the total cross-sectional area of the said tubes greater than the area of the exhaust pipe of the engine, and a casing housing the said tubes, there being openings leading from the interior of said casing to the outer air and to the air intake 90 passage of the engine respectively; and a plurality of air-deflecting partitions within 95 said casing transverse to the said tubes. 100

4. A muffler for internal combustion engines, comprising a substantially cylindrical enlargement of the exhaust passage of the engine; perforated heads positioned at each end of the said enlargement; tubes mounted at their opposite ends in the perforations of the said heads, the total cross-sectional area of said tubes greater than that of the said exhaust passage; and a passage leading from one end of the cylindrical enlargement to the air-intake of the engine; there being an opening in the said substantially cylindrical enlargement in proximity to its other end. 105

5. A muffler for internal combustion engines, comprising a substantially cylindrical enlargement of the exhaust passage of the engine; perforated heads positioned at each end of the said enlargement; tubes mounted at their opposite ends in the perforations of the said heads, the total cross-sectional area of said tubes greater than that of the said 110 exhaust passage; and a passage leading from one end of the cylindrical enlargement to the air-intake of the engine; there being a plurality of openings in the said substantially cylindrical enlargement in proximity 115 to its other end. 120

6. A muffler for internal combustion engines, comprising a substantially cylindrical enlargement of the exhaust passage of the engine; perforated heads positioned at each 130

end of the said enlargement; tubes mounted at their opposite ends in the perforations of the said heads, the total cross-sectional area of said tubes greater than that of the 5 said exhaust passage; and a passage leading from one end of the cylindrical enlargement to the air-intake of the engine; there being an opening in the said substantially cylindrical enlargement in proximity to its 10 other end; and an air-deflecting partition transverse of the said cylindrical enlargement and positioned therein between the said passage and the said opening.

7. A muffler for internal combustion engines, comprising a substantially cylindrical enlargement of the exhaust passage of the engine; perforated heads positioned at each end of the said enlargement; tubes mounted at their opposite ends, in the perforations 15 of the said heads, the total cross-sectional area of said tubes greater than that of the said exhaust passage; and a passage leading from one end of the cylindrical enlargement to the air-intake of the engine; there 20 being a plurality of openings in the said substantially cylindrical enlargement in proximity to its other end; and an air-deflecting partition transverse of the said cylindrical enlargement and positioned therein 25 between the said passage and the said opening.

8. A muffler for internal combustion engines, comprising a substantially cylindrical enlargement of the exhaust passage of the engine; perforated heads positioned at each 30 end of the said enlargement; tubes mounted at their opposite ends in the perforations of the said heads, the total cross-sectional area of said tubes greater than that of the said 35 exhaust passage, and a passage leading from one end of the cylindrical enlargement to the air-intake of the engine; there being a plurality of openings in the said substantially cylindrical enlargement in proximity to its other end; and a plurality of air-deflecting partitions transverse of the said en- 40

largement and positioned therein between the said opening and the juncture of the enlargement with the said passage.

9. A muffler for an engine having an exhaust passage and an air-intake passage, comprising an expansion chamber connected to the said exhaust passage; a plurality of tubes leading from the said expansion chamber to an exhaust pipe opening into the outer 50 air; and a casing housing the said tubes, the interior of said casing connected in proximity to the opposite ends of the said tubes with the outer air and with the said intake passage of the engine respectively. 60

10. A muffler for an engine having an exhaust passage and an air-intake passage, comprising an expansion chamber connected to the said exhaust passage; a plurality of tubes leading from the said expansion chamber to an exhaust pipe opening into the outer air; and a casing housing the said tubes and expansion chamber, the interior 65 of said casing connected in proximity to the opposite ends of the said tubes with the outer air and with the said intake passage of the engine respectively. 70

11. A muffler for an engine having an exhaust passage and an air-intake passage, comprising an expansion chamber connected 75 to the said exhaust passage; a plurality of tubes leading from the said expansion chamber to an exhaust pipe opening into the outer air; and a casing housing the said tubes, the interior of said casing connected 80 to the said exhaust passage; a plurality of tubes leading from the said expansion chamber with the outer air and with the said intake passage of the engine respectively; and air-deflecting partitions transversely mounted within the said casing. 85

In testimony whereof I have signed my name in presence of two subscribing witnesses.
